(57) **CLAIM**

The ornamental design for a case, as shown and described.

DESCRIPTION

FIG. 1 is a back, bottom and side perspective view of a case in a closed position embodying my new design;

FIG. 2 is a first side view thereof with arms for securing an electronic device in a lowered position;

FIG. 3 is a second side view thereof;

FIG. 4 is a back view thereof;

FIG. 5 is a front view thereof;

FIG. 6 is a top view thereof, the bottom view being a mirror image;

FIG. 7 is a front, bottom and side perspective view of the case in an open position with arms for securing an electronic device shown in a lowered position;

FIG. 8 is a first side view thereof;

FIG. 9 is a second side view thereof;

FIG. 10 is a front view thereof;

FIG. 11 is a back view thereof;

FIG. 12 is a bottom view thereof, the top view being a mirror image;

FIG. 13 is a front, bottom and side perspective view of the case in an open position with arms for securing an electronic device in a raised position;

FIG. 14 is a front, bottom and side perspective view thereof, with arms for securing an electronic device in a lowered and expanded position containing an unclaimed electronic device; and,

FIG. 15 is an enlarged view of the encircled portion shown in FIG. 7.

Broken lines are used to illustrate features of the case which form no part of the claimed design. Lines with a long dash followed by two short dashes are used to represent stitching which forms no part of the claimed design. The dash-dash-dot boundary line **15-15** in FIG. 7 identifies a portion of the figure which is shown enlarged in FIG. 15. The dash-dash-dot boundary lines in FIG. 7 and FIG. 15 form no part of the claimed design. The evenly broken lines in FIG. 14 illustrate an unclaimed electronic device being held in the case.

1 Claim, 13 Drawing Sheets
